MACHINE FOR APPLYING TAPE TO
SHOE PARTS

Harry D. Elliott, Wenham, Mass., assignor to
United Shoe Machinery Corporation, Flemington, N. J., a corporation of New Jersey

Application July 26, 1947, Serial No. 763,921

6 Claims. (Cl. 12—59.5)

1

This invention relates to machines for applying tape to shoe parts and is herein illustrated and described as embodied in a machine of the type disclosed in United States Letters Patent No. 2,335,267, granted November 30, 1943, upon my application, for applying a precoated reinforcing tape to the throats of vamps for blucher and bal type shoes. The purpose of the tape is to reinforce the vamp throat along that portion to which the quarters of the shoe are to be attached in order to strengthen the connection and to prevent the attaching means from pulling out under the strain of the lasting operation and particularly the strain of removing the last in the course of manufacture. The reinforcing tape is applied on the lengthwise center line of a bal type vamp. In the case of blucher type vamps it is desirable to apply two pieces of tape, one on each side of the lengthwise center line.

It is an object of the present invention to provide a tape applying machine of the character above described having improved means for gaging a vamp in relation to the tape applying instrumentalities. In accordance with a feature of the invention the illustrated machine is provided with a gage transversely movable between two operating positions wherein it gages a blucher vamp for the application of separate pieces of reinforcing tape at opposite sides of the vamp throat. The illustrated machine is further provided with another gage for gaging a bal vamp for the application of a single piece of reinforcing tape at the center of the vamp throat, the bal vamp gage being so constructed and arranged that when it occupies its operative position it serves to hold the blucher vamp gage in a neutral position.

These and other features of the invention will appear more fully from the following detailed description when read in connection with the accompanying drawings and will be pointed out in the appended claims.

Referring now to the accompanying drawings,

Fig. 1 is a plan view of the machine with the cover broken away to show portions of the operating mechanism;

Fig. 2 is a plan view of the gaging mechanism showing a bal vamp in gaged position;

Fig. 3 is a side elevation, partly in section, showing the gaging mechanism;

Fig. 4 is a front elevation of the gaging mechanism in position for operating upon a bal vamp;

Fig. 5 is a plan view similar to Fig. 2 but showing the gaging mechanism arranged to position a blucher vamp; and

2

Fig. 6 is a front elevation similar to Fig. 4 but showing the gaging mechanism arranged to operate upon a blucher vamp.

The supporting structure of the illustrated machine consists of a hollow casing 10 having a removable cover 12 (Fig. 2), the forward portion of which serves as a work table 14 for supporting, flesh side down, a bal vamp 16 as shown in Fig. 2 or a blucher vamp 18 as shown in Fig. 10. While, for convenience, the work table 14 is shown in a horizontal position, it actually slopes downwardly and forwardly, the entire cover 12 being tilted at about the same inclination as the cover disclosed in Letters Patent No. 15 2,335,267, above mentioned.

The illustrated machine is further provided with a mechanism 20 (Fig. 1) for guiding a strip 22 of adhesive tape which is drawn, coated side up, from a reel positioned at the left of the 20 machine. The tape 22 passes beneath the work table 14 through a groove, not shown, in the under surface of the cover 12 and it is fed by mechanism comprising a feed bar 24 which reciprocates in guideways in the casing 10. Such 25 movement of the feed bar 24 is effected by a lever 28 which is fulcrumed upon a pin 30 adjustable from front to back to vary the length of stroke of the feed bar. The rearward end of the lever 28 carries a cam roll which engages a groove 30 formed on a cam 32. This cam 32 is carried by a shaft 34 journaled in suitable bearings in the casing 10 and driven by a pulley 36 over which runs a belt 38 connected to any suitable source of power.

35 The tape 22 passes over a hardened steel plate 40 which is reciprocated heightwise to apply the tape to the under surface of the vamp 16 or 18, a suitable opening being formed in the work table 14 to provide access to the vamp. The 40 left hand edge of the plate 40 also operates as a shear blade in cooperation with a stationary shear blade 42 to sever a piece of tape 43 (Fig. 2) which is to be applied to a bal vamp, or a piece of tape 45 (Fig. 5) which is to be applied to a blucher vamp. The plate 40 is carried by a block 44 mounted on a lever 46 which is fulcrumed upon a pin 43. Upon the rearward end of the lever 46 is formed a yoke 49 which embraces a cam 50 secured upon the shaft 34 to rock the lever 50 46 heightwise. The block 44 is secured to the lever 46 through an arcuate tongue-and-groove connection to provide for angular adjustment of the left-hand edge of the plate 40 with respect to the shear blade 42 and it is clamped in adjusted 55 position by two screws 52.

The upward thrust of the block 44 in applying the piece of tape 43 or 45 to the vamp is resisted by a transparent block 56 of plastic or nonshatterable glass carried by a pair of arms 58 which are pivotally mounted upon a fulcrum pin 60 and are integrally connected at their rear ends by a cross piece 62. The transparent block 56 bridges the forward ends of the arms 58, the lateral edges of the block being beveled for dovetail engagement with complementary notches formed in the arms as shown in Figs. 4 and 6. In order to hold the block 56 securely clamped between the arms 58, a screw 64 has a smooth shank portion extending through a hole in one of the arms and an end portion threadedly engaging the other arm, the arms being sufficiently resilient to accommodate the slight movement necessary for clamping the block.

The fulcrum pin 60 is mounted in a bracket 66 having a lower portion which is embraced by the arms 58. The bracket 66 has also an upper rearwardly extending portion which terminates in a slide 68 having tongue-and-groove engagement with a guideway 70 formed on a steeply inclined portion of the cover 12. The guideway 70 extends transversely of the machine for the purpose of enabling the bracket 66 and the various members which it supports to be adjusted toward the right or the left in accordance with the length of the piece of tape 43 or 45 to be applied. Inasmuch as the left-hand end of this piece of tape, as viewed from the front of the machine, always coincides with the stationary edge of the shear blade 42, the position of the center line of the piece of tape will depend upon the length of the piece of tape. The transverse adjustment, therefore, of the bracket 66 thus enables the various parts carried by the block to be centered with respect to the piece of tape. For convenience in adjusting the bracket 66, the slide 68 is provided with a pointer 72 which cooperates with a stationary scale 74 secured upon the cover 12. The slide 68 is secured in its adjusted position in the guideway 70 by clamping screws 75 which pass through slots in the slide 68. For the transverse positioning of bal vamps a center line 76 is provided on the transparent block 56, the operator moving the vamp to the right or left until a mark on the vamp comes into register with the center line 76.

The transparent block 56 is yieldingly held down against the upward thrust of the presser block 44 by a spring 78 (Fig. 3) housed in a bore 80 in the cross piece 62. The upper end of the spring 78 bears against an internal shoulder of the bore 80 and the lower end of the spring 78 bears against a washer 82 backed by a nut 84 threaded upon a reduced lower end portion of a screw 86. The upper portion of the screw 86 is of greater diameter than the lower portion and is threaded into the upper and rearwardly extending portion of the bracket 66. A shoulder 87 on the screw 86 engages the cross piece 62 to hold the latter against the upward thrust of the spring 78 and thereby determines the normal height of the transparent block 56 above the plane of the work table 14. This normal height can be varied by turning the screw 86, the screw being held in adjusted position by a lock nut 88. The portion of the screw 86 which is below the shoulder 87 passes down through an opening in the cross piece 62 large enough to permit free pivotal movement of the arms 58 about the pin 60.

The illustrated machine as so far described, except for differences in the design of some of its

parts, and the provision for angular adjustment of the plate 40, is similar to the machine disclosed in United States Letters Patent No. 2,335,267 above mentioned.

The machine illustrated herein is provided with a gage 90 for gaging a bal vamp. As shown in Fig. 2, the bal vamp 16 has an edge 92 extending across the base of its throat recess. The purpose of the gage 90 is to serve as a rearward stop for the edge 92 when the operator positions the vamp upon the work table 14. The gage 90 is in the form of a slide and it is guided for heightwise movement in a guideway formed in an upstanding portion of a bracket 94. The gage 90 is frictionally retained in a desired heightwise position in its guideway by a light clamping pressure exerted by a spring washer 93 backed by the head of a screw 95 extending through a heightwise slot 97 in the gage and threaded into the bracket. The bracket 94 has a horizontal rearwardly extending portion which is rigidly secured by a clamping screw 96 to a forwardly extending portion 98 of the bracket 66. The screw 96 has a clamping shoulder 100 which bears against the bracket 94 and a threaded lower end portion 102 which is threaded down into the extension 98. A slot 104 formed in the bracket 94 to accommodate the screw 96 permits the bracket 94 to be adjusted forwardly and rearwardly. Excessive forward adjustment of the bracket 94, which might result in bringing the gage 90 into the path of heightwise movement of the plate 40, is prevented by a stop 101 secured in the bracket 66 by a set screw 103 and engageable with a shoulder 105 on the bracket 94. The gage 90 is shown in Figs. 3 and 4 as occupying its lowermost position, with its lower edge in contact with the work table 14, wherein it is operative to engage a work piece. It may, however, be raised to an out-of-the-way position as shown in Fig. 6 and, for the convenience of the operator in thus moving it in its guideway, a finger hole 106 is provided in its upper portion. The lower end of the gage 90, as shown in Figs. 4 and 6, is centrally recessed, for a purpose later to be described, leaving two spaced work engaging portions 108.

For determining the position of the blucher vamp 18 (Fig. 5), the illustrated machine is provided with a gage 112 in the form of a forwardly extending bar having at its forward end a rounded work engaging portion 114. The rear portion of the gage 112 is slidably mounted for forward and rearward adjustment in a guideway 115 (Fig. 3) formed in the under surface of a head 116 integral with the lower end of a sleeve 118 which is pivotally mounted in a bearing formed in the bracket 66 to enable the gage 112 to swing transversely of the machine about the axis of the sleeve. The gage 112 can thus be adjusted in its guideway forwardly and rearwardly, or radially with respect to the axis of the sleeve 118, and it is clamped in its guideway by a bolt 120 extending upwardly through the sleeve 118 and having at its lower end a square head 122, two edges of which engage the sides of the guideway 115 to prevent turning of the bolt relatively to the sleeve 118. The shank of the bolt 120 passes through a slot formed in the gage 112 lengthwise thereof to permit forward and rearward adjustment of the gage. Such adjustment is facilitated by a pair of finger grips 124 formed on the rear end of the gage. Secured upon the upper end portion of the sleeve 118 is a split block 126 having a clamping screw 128 by means of which the split portion of the block can be tightly drawn together

to clamp the block on the sleeve. For the purpose of positively preventing turning movement of the block 126 relative to the sleeve 118, a key 130 engages suitable recesses in the sleeve and the block. The sleeve 118 is retained against axial movement in its bearing in the bracket 66 by the head 119 formed on the lower end of the sleeve and the block 126 clamped to its upper end portion. A knurled nut 132 threaded upon the upper end portion of the bolt 120 and bearing against the upper surface of the block 126 tightens the bolt to clamp the gage 112 in its position of forward and rearward adjustment. It is evident that the gage 112, the sleeve 118, the bolt 120, and the block 126 can all turn pivotally as a unit about the axis of the sleeve 118.

In order to limit such swinging movement of the gage 112 toward the right and left, the block 126 is provided with a pair of forwardly extending ears 134 having their adjacent edges angularly disposed to define a V-shaped recess into which extends an upstanding pin 136. This pin 136 is rigidly mounted in a slide 138 which is movable forwardly and rearwardly in a suitable guideway formed in the upper portion of the bracket 66. The forward and rearward position of the pin 136 is adjusted by turning a knurled head 140 of a screw 142 which is threaded horizontally into the bracket 66. The slide 138 has a depending lug 144 which is recessed to enable it to engage a groove formed in a smooth portion of the head of the screw 142. It is evident that turning of the head 140 will adjust the pin 136 toward or from the vertex of the V-shaped recess provided between the ears 134 and thereby vary the extent to which the block 126 can be turned by reason of one of the other walls of the V-shaped recess engaging the pin 136. Thus if the pin 136 is adjusted to a forward position the amplitude of the swinging movement of the gage 112 will be relatively great and if the pin 136 is adjusted to a rearward position this amplitude will be relatively small.

When bal vamps are being operated upon and the use of the blucher gage 112 is not required, the blucher gage is swung into a neutral position wherein its work engaging portion will extend into the recess between the two spaced work engaging portions 108 (Fig. 4) of the bal gage 90. Then, when the bal gage 90 is lowered into operating position, it will hold the blucher gage 112 in this neutral position. Excessive forward adjustment of the blucher gage 112, which might bring it into the path of heightwise movement of the plate 40, is prevented by a shoulder 146 (Fig. 6) on the blucher gage which is engageable with the rear surface of the bal gage 90.

When blucher vamps are being operated upon, the bal gage 90 is raised to bring it into its out-of-the-way position (Fig. 6) and to release the blucher gage 112 for lateral swinging movement. The blucher gage 112 may then be swung to its right-hand limiting position, as shown in Fig. 5, to gage the vamp 18 for the application of the piece of tape 45 to the vamp at the left-hand side of the vamp throat. After the piece of tape 45 has thus been applied, the gage 112 is swung to its left-hand limiting position and a similar piece of tape is applied at the right-hand side of the vamp throat. The line 76 on the transparent block 56, while helpful in centering bal vamps, is not necessary in work upon blucher vamps, which are gaged solely by the gage 112. Most blucher vamps have re-entrant portions at the sides of their throats into which the work engaging por-

tion 114 of the gage 112 extends, and in any case, the blucher gage 112 alone is sufficient to enable the operator to gage a blucher vamp both forwardly and rearwardly and also laterally.

Having thus described my invention, what I claim as new and desire to secure by Letters Patent of the United States is:

1. In a machine for applying tape to shoe vamps, means for applying pieces of tape to a vamp, a gage engageable alternatively with two transversely spaced portions of the throat of a blucher vamp, and a support whereon said gage is movable between two operating positions in one of which it gages the vamp relatively to the tape applying means to insure the application of a piece of tape at a desired locality at one side of the vamp throat and in the other of which positions it gages the vamp relatively to the tape applying means to insure the application of a second piece of tape at a desired locality at the other side of the vamp throat.
2. In a machine for applying tape to shoe vamps, means for applying pieces of tape to a vamp, a gage engageable alternatively with two transversely spaced portion of the throat of a blucher vamp, a support whereon said gage is movable between two operating positions in one of which it gages the vamp relatively to the tape applying means to insure the application of a piece of tape at a desired locality at one side of the vamp throat and in the other of which positions it gages the vamp relatively to the tape applying means to insure the application of a second piece of tape at a desired locality at the other side of the vamp throat, and movably mounted means cooperating with said gage adjustably to determine the spacing of said positions.
3. In a machine for applying tape to shoe vamps, means for applying pieces of tape to a vamp, a gage engageable alternatively with two transversely spaced portions of the throat of a blucher vamp, a support whereon said gage is movable between two operating positions in one of which it gages the vamp relatively to the tape applying means to insure the application of a piece of tape at a desired locality at one side of the vamp throat and in the other of which positions it gages the tape relatively to the tape applying means to insure the application of a second piece of tape at a desired locality at the other side of the vamp throat, and a separate gage for bal vamps cooperating with the blucher gage to render the blucher gage inoperative when the bal gage is in use.
4. In a machine for applying tape to shoe vamps, means for applying pieces of tape to a vamp, a gage engageable alternatively with two transversely spaced portions of the throat of a blucher vamp, a support upon which said gage is pivotally mounted for swinging movement between two operating positions in one of which it gages the vamp relatively to the tape applying means to insure the application of a piece of tape at a desired locality at one side of the vamp throat and in the other of which positions it gages the vamp relatively to the tape applying means to insure the application of a second piece of tape at a desired locality at the other side of the vamp throat, and stop means for determining the operating positions of the gage, said stop means comprising a pair of elements one of which is an abutment and the other of which is a member having a V-shaped recess the sides of which are engageable with said abutment, one of said stop elements being secured to said gage, the other

stop element being movable on said support relatively to the one on the gage to vary the extent of swinging movement permitted by the V-shaped recess.

5. In a machine for applying tape to shoe vamps, means for applying pieces of tape to a vamp, a support, a gage movable transversely thereon between two operating positions wherein it is engageable alternatively with two transversely spaced portions of the throat of a blucher vamp to gage the vamp relatively to the tape applying means to insure the application of two pieces of tape at desired localities adjacent to the respective sides of the vamp throat, and another gage on the support engageable with the throat recess of a bal vamp to gage the vamp forward and rearward relatively to the tape applying means, said bal vamp gage having a recess to accommodate the blucher vamp gage when the latter occupies a neutral position intermediate between its operating positions and to hold the blucher vamp gage in said neutral position, said bal vamp gage being movable on said support from an operating position wherein it holds the

blucher vamp gage in said neutral position to an out-of-the-way position wherein it releases the blucher vamp gage for transverse movement.

6. In a machine for applying tape to shoe vamps, a pair of tape applying members arranged to receive between them a piece of adhesive tape and a vamp, a support for one of said members, means for moving one of said members towards the other to apply the piece of tape by pressure to the vamp, a gage for blucher vamps mounted on said support for movement between two operating positions, and a gage for bal vamps adjustably mounted on said support for movement between an out-of-the-way position and an operating position which is intermediate between the operating positions of the blucher vamp gage, said bal gage being constructed and arranged when in its operating position to hold said blucher vamp gage in said intermediate position without hindering the use of the bal vamp gage.

HARRY D. ELLIOTT.
